UNITED STATES PATENT OFFICE.

JOHN B. HUGHES AND HENRY H. BACON, OF COZAD, NEBRASKA.

DESIGN FOR A STAPLE.

SPECIFICATION forming part of Design No. 29,472, dated October 11, 1898.

Application filed September 7, 1898. Serial No. 690,442. Term of patent 14 years.

To all whom it may concern:

Be it known that we, JOHN B. HUGHES and HENRY H. BACON, citizens of the United States, residing at Cozad, in the county of 5 Dawson and State of Nebraska, have invented and produced a new and original Design for Staples, of which the following is a specification, reference being had to the accompanying drawing, forming part thereof, which is a 10 perspective view illustrating our new design.

The leading feature of our design resides in the U-shaped form of the staple and the rectangular-shaped head arranged thereon, and referring especially to the drawing, A indicates the tapered prongs or legs flattened 15 near their ends, as shown at B, and having their inner sides tapered off, as shown at C,

20 said tapering legs being connected by a curved top D of the same general sectional contour, and the head E, essentially rectangular in shape and substantially as long and wide as the curved top, is joined to the said top at the inner ends of the tapering or inclined sides F and similarly-shaped ends G.

Having described our invention, what we 25 claim as new, and desire to secure by Letters Patent, is—

The design for a staple, as herein shown and described.

JOHN B. HUGHES.
HENRY H. BACON.
